UNITED STATES PATENT OFFICE

2,502,329

PACKAGE FILLING SPOUT FOR ICE CREAM MACHINES

Richard J. H. Lane, Santa Cruz, Calif.

Application September 7, 1948, Serial No. 47,996

1 Claim. (Cl. 222—561)

1

This invention relates to, and it is an object to provide, a package filling spout unit for ice cream machines of the type known as batch freezers, and which machines are operative to feed soft ice cream. Conventionally this type of machine is fitted with a discharge spout not readily adaptable to packaging the ice cream in paper cartons.

It is therefore an object of this invention to provide a spout unit, for ice cream machines, adapted for effective use to fill paper cartons, such as pints and quarts, with ice cream; the spout unit being designed so that open-ended paper cartons can be applied, manually and successively, to the spout conveniently and quickly, whereby the output is substantial.

Another object of the invention is to provide a package filling spout unit, as above, which includes a novel valve assembly for controlling the flow of ice cream, fed from the machine, through the spout.

A further object of the invention is to provide a package filling spout unit adapted to be applied as an attachment to existing batch type ice cream machines, or can be an accessory to the machine as manufactured.

It is also an object of the invention to provide a package filling spout unit which is simple in construction, whereby it can be manufactured economically.

A further object of the invention is to provide a practical and reliable package filling spout unit, and one which will be exceedingly effective for the purpose for which it is designed.

These objects are accomplished by means of such structure and relative arrangement of parts as will fully appear by a perusal of the following specification and claim.

In the drawings:

Fig. 1 is a front elevation of an ice cream machine, shown somewhat diagrammatic, with the spout unit mounted thereon; the valve being closed.

Fig. 2 is an enlarged cross section on line 2—2 of Fig. 1.

Fig. 3 is a view similar to Fig. 1, but shows the valve removed to open the spout unit.

Fig. 4 is an enlarged cross section on line 4—4 of Fig. 3.

Referring now more particularly to the characters of reference on the drawings, the numeral 1 indicates generally the forward end portion of an ice cream machine of the type known in the trade as a batch freezer, which machine is op-

2

erative to feed soft ice cream as a continuous stream for the duration of each batch.

At its forward end portion 1 the ice cream machine includes an access plate 2 normally maintained in a closed position by a latched retention bar 3; the access plate including, adjacent the top thereof, a filling hopper 4, through which the ingredients are poured into the machine.

Below the closure bar 3 the machine is fitted 10 with the spout unit, indicated generally at 5, which forms the subject of the present invention.

The access plate 2 is provided, below the closure bar 3, with a mounting base 6 which defines an ice cream discharge opening 7; the machine being 15 operative to feed soft ice cream outwardly through the opening 7 in a continuous stream. A valve casing 8 is secured to the mounting base 6 of the access plate 2 and projects forwardly therefrom; such valve casing 8 including a passage or throat 9 which matches the ice cream discharge opening 7. The valve casing 8 is of limited extent longitudinally, and its forward end is cut at a downward and inward incline.

A supporting plate 10 is affixed to the outer 25 end of a valve casing 8, in matching face to face relation, by means of screws 11. The supporting plate 10 is formed as a laterally radiating flange on the inner end of a spout 12, thus supporting said spout in fixed relation to the valve casing 8 30 in communication with passage 9. The spout 12 is rectangular in cross section and projects from the plate 10 at a forward and downward incline for engagement in a package, as will be explained hereinafter.

35 The passage 9 through the valve casing 8 is normally closed by a wedge-shaped valve 13, rectangular in front elevation, which projects downwardly through a matching slot 14 in the top of the valve casing 8. When the wedge-shaped 40 valve 13 is in its fully closed position, its lower end engages in a matching, internal groove or channel 15 in the lower portion of the valve casing 8. This groove or channel extends up both sides of said valve casing 8, as shown.

45 The fully lowered or closed position of the wedge shaped valve is shown in Figs. 1 and 2; the valve then preventing any flow of ice cream through the spout 12.

When the spout unit 5 is to be used for filling 50 ice cream packages or cartons, the wedge shaped valve 13 is first removed from said spout unit by pulling upwardly thereon; there being a forwardly projecting handle 16, for this purpose, on the valve 13 adjacent its upper end. Once the 55 valve 13 is removed, soft ice cream begins to flow

through the opening 7, passage 9, and spout 12. The ice cream cartons, one of which is indicated at 17, are then engaged, manually and successively, with the spout 12 in carton filling relation; the spout fitting closely in the open end of each such carton. As each carton fills, it is removed and another is immediately replaced; the operation being accomplished quickly, readily, and conveniently, by hand, so that production is substantial. When the wedge-shaped valve 13 is removed, for use of the spout unit 5, it is necessary to close the slot 14, as otherwise soft ice cream would escape upwardly therethrough; such closure of the slot 14 being accomplished as follows:

The top of the valve casing 8 is formed with a transverse guideway 18 which extends along the slot 14 for the full length of the latter, and opens to one side of said casing. A flat, elongated, shutter 19 is slidably engaged in said transverse guideway 18; being initially retracted to a position clear of the slot 14, as in Fig. 1, to permit of engagement of the valve 13 through said slot. However, when the valve 13 is removed for use of the spout unit 5, as in Fig. 3, the shutter 19 is advanced until it closes the slot 14; there being a finger piece 20 on the outer end of the shutter 19 for the purpose of effecting movement of the latter. After the spout unit 5 has been used, and it is desired to shut off the flow of ice cream, the shutter 19 is retracted with one hand and the valve 13 is inserted through the slot 14 and moved to closed position by the other hand; all being accomplished quickly and easily.

From the foregoing description it will be readily seen that there has been produced such a device as substantially fulfills the objects of the invention, as set forth herein.

While this specification sets forth in detail the

present and preferred construction of the device, still in practice such deviations from such detail may be resorted to as do not form a departure from the spirit of the invention, as defined by the appended claim.

Having thus described the invention, the following is claimed as new and useful, and upon which Letters Patent are desired:

A spout unit for an ice cream machine which includes a mounting member having an ice cream discharge opening therethrough, said spout unit comprising a valve casing secured in matching engagement with said mounting member, there being a passage in the valve casing communicating with said opening in the mounting member, a spout in communication with and projecting forward from the valve casing, means securing the spout to said valve casing, the latter having a transverse slot in the top thereof, a plate-like valve projecting through the slot in matching relation and closing said passage, the valve being manually removable from above, and a normally retracted shutter mounted on the valve casing for sliding motion to close the slot when the valve is removed.
